UNITED STATES PATENT OFFICE

RUDOLPH BECKER, OF NORTH PLAINFIELD, NEW JERSEY, ASSIGNOR TO THE SINGER MANUFACTURING COMPANY, OF ELIZABETH, NEW JERSEY, A CORPORATION OF NEW JERSEY

HAT-SEWING MACHINE

Application filed October 26, 1926. Serial No. 144,209.

This invention relates to sewing machines and has for an object to provide a sewing machine having a novel form of frame which is particularly adapted for stitching operations on hats. Further objects of the invention are to provide the machine with simple needle-bar operating and feeding mechanisms. Further objects of the invention will appear from the following description and 10 claims.

The frame comprises a hollow casting having a vertical standard from the top of which extends a lateral bracket-arm having its free end curved downwardly; said arm having a 15 smoothly curved and unobstructed upper surface and being devoid of upward projections, whereby the crown of a hat may, without difficulty, be extended over the end of such bracket-arm during a sewing operation. 20 Joining the standard adjacent the base of the latter is a hollow work-supporting arm which is inclined at an angle to the standard and at its free end carries a horizontal throat-plate directly under the free end of the bracket- 25 arm, which bracket-arm carries a reciprocating needle-bar and spring-pressed presser-bar.

The stitch-forming and feeding mechanisms within the frame preferably derive 30 their movements from a short horizontal main-shaft which is journaled in the standard in a plane parallel to the plane of the needle-bar and work-supporting arm. This shaft may be geared to a vertical drive shaft with- 35 in the standard, which shaft is connected at its upper end to the needle-bar operating mechanism and at its lower end to a looper-shaft extending lengthwise of and within the inclined work-supporting arm; such looper- 40 shaft at its free end carrying a rotary chain-stitch looper. The feeding mechanism in the specific embodiment herein disclosed comprises a novel form of feed-bar and actuating mechanism adapted to the present frame 45 structure. The feed-bar extends lengthwise

of and within the inclined work-supporting arm, below the looper-shaft, and upwardly within the standard to a point substantially level with the throat-plate where it is anchored to the frame by a universal or ball joint. Below the ball joint and preferably within the standard is a feed-bar guide which is entered by a downward extension of the feed-bar and confines the motion of the vertical portion of the feed-bar to the plane parallel to the vertical plane of the work-supporting arm. The inclined looper-shaft preferably carries within and near the free end of the work-supporting arm a feed-lift eccentric and an adjustable feed-advancing eccentric which may be connected through suitable mechanism to the feed-bar on the free end of which is mounted a feed-dog extending upwardly through the throat-plate. 50 55 60

In the accompanying drawings Fig. 1 is a rear side elevation of a sewing machine embodying the invention. Fig. 2 is a front end elevation. Figs. 3 and 4 are, respectively, enlarged sections on the lines 3-3 and 4-4, Fig. 1. Fig. 5 shows the portion of the looper-shaft which carries the feed-eccentrics. Fig. 6 shows the portion of the feed-bar to which the feeding connections are made. Fig. 7 is a section on the line 7-7, Fig. 1; and Fig. 8 is a plan view, partly diagrammatic, of the feeding mechanism. 65 70 75

In the preferred embodiment of the invention illustrated, the frame casting comprises a hollow vertical standard 1 having a base 2. Extending laterally from the upper end of the standard 1 is the hollow bracket-arm 3 which is curved downwardly at its free end 4 which carries the reciprocating needle-bar 5 and presser-bar 6. The bracket-arm 3 has a smooth and unobstructed surface, devoid of upward projections, so that the crown of a hat A (in full lines) Fig. 1, may be readily thrown over the free end of the bracket-arm during a stitching operation. 80 85 90

Extending at an angle to the standard 1 and

joining the standard adjacent the base 2 is the hollow inclined work-supporting arm 7 carrying at its free end the horizontal throat or cloth-plate 8 and removable end cap 9. The inclined arm 7 facilitates many stitching operations on hats and avoids the necessity of unduly distorting the latter. For top-stitching the crown of the hat A (dotted lines, Fig. 1) it may be placed over the end of the arm 7. A detachable bridge member 10 may be inserted between the throat-plate 8 and the standard 1 when an extended flat work-support is desired.

Journaled in bearings 11, 12, within the standard 1, is the vertical drive shaft 13 to the upper end of which is secured the balanced crank 14. The shaft 13 extends through the lubricant cavity 15, cast within the standard 1, and has fixed thereto within such cavity a bevel gear 16 with which meshes a bevel gear 17 carried by the inner end of the horizontal main-shaft 18 journaled in the standard 1 in parallelism with the plane of the needle-bar 5 and work-supporting arm 7. The cavity 15 is closed by an inner cover-plate 15'. The main-shaft 18 carries a suitable belt-pulley and balance-wheel 19. The lubricant cavity 15 may be packed with a suitable gear lubricant which is closely confined with the gears 16, 17.

The needle-bar 5 carrying the eye-pointed needle 20 is connected by the link 21 to the forwardly extending arm 22 of a bellcrank-lever fulcrumed at 23 in the downwardly curved end 4 of the bracket-arm 3. The up-standing arm 24 of the bellcrank-lever is connected by a ball-and-socket joint to the pitman 25 which extends lengthwise of and within the bracket-arm 3 and has a ball-and-socket connection with the crank 14. This needle-bar operating mechanism is simple and particularly well adapted for use within a hollow bracket-arm having a downwardly curved free end and no obstructions on its upper smoothly curved surface.

The presser-bar 6 carries a presser-foot 26 which is pressed upon the work by the leaf spring 27 housed within the hollow arm 3. The spring 27 is anchored at one end to the pin 28 and at its free end rests upon the top end 29 of the presser-bar. The thumb-screw 30 bearing upon the spring 27 is used to adjust the pressure thereof upon the presser-bar. The usual cam-lever 31 is used to lift the presser-foot. It acts upon the lateral pin 32 fixed to the presser-bar. A needle-thread take-up 33 is carried by the needle-bar 5.

Journaled within and longitudinally of the inclined work-supporting arm 7 is the looper-shaft 34 which is geared at 35 to the vertical shaft 13 and at its upper end carries a rotary chain-stitch looper 36.

The feeding mechanism comprises a four-motion feed-bar of angular form including a vertical portion 37 within the standard 1 and

an inclined portion 38 within the work-supporting arm 7, joined rigidly together by means of the connecting arm 39. The portion 37 of the feed-bar is hung from the ball-stud anchorage 40 within the standard 1 and at its lower end enters the guide-slot 41 adjacent the base 2. Secured to the free end of the inclined portion 38 of the feed-bar is the carrier 42 for the feed-dog 43. It will be observed that the ball and socket joint 40 constitutes a fixed universal-joint connection between one end of the feed-bar and the sewing machine frame within the standard, such universal-joint connection being fixed in the sense that it has no bodily movement as a whole relative to the sewing machine frame. Also, it will be observed that the universal-joint connection 40 is about on a level with the cloth-plate 8 so that the swinging movement of the feed-bar about such connection will give to the feed-dog substantially vertical rising and falling movements, such movements being derived from the ballcrank or eccentric 44 which is connected by the link 45 to the ball 46 on the feed-bar member 38.

Feed-and-return movements are imparted to the feed-bar by means of the adjustable eccentric 47 carried by the looper-shaft 34. The eccentric 47 is embraced by the forked arm 48 of a bellcrank-lever journaled on the stationary stud-pin 49 and including a downwardly extending arm 50 which is connected by the link 51 to the ball 52 on the feed-bar member 38. Mounted on the feed-dog carrier 42 is a roller-stud 53 which enters a guide-slot 54 in a member fixed to the arm 7. The guide-slot 54 is very slightly curved in a horizontal plane about the ball-stud 40 as a center, and the roller 53 is slightly barrel-shaped so as not to cramp in the guide-slot during the rising-and-falling movements of the feed-dog. The present feeding mechanism is particularly well adapted for incorporation in a work-supporting arm, and particularly in an inclined work-supporting arm, for feeding across the arm.

Having thus set forth the nature of the invention, what I claim herein is:

1. A sewing machine having a frame including a base, a hollow vertical standard rising from said base, a hollow bracket-arm extending laterally from the upper end of said standard, the upper surface of said bracket-arm being smoothly curved downwardly to the free end of such arm and devoid of upward projections, a hollow work-supporting arm inclined at an angle to said standard and joining the latter adjacent said base, stitch-forming and feeding mechanisms incorporated in said frame, said feeding mechanism being disposed within said work-supporting arm and arranged to feed the work transversely of the vertical plane of said work-supporting arm.

2. A sewing machine having a frame in-

- cluding a base, a hollow vertical standard rising from said base, a hollow bracket-arm extending laterally from the upper end of said standard, the upper surface of said bracket-arm being smoothly curved downwardly to the free end of such arm and devoid of upward projections, a hollow work-supporting arm inclined at an angle to said standard and joining the latter adjacent said base, a vertical drive shaft disposed in said standard and having a crank at its upper end, a reciprocating needle-bar carried by said bracket-arm and connected to be actuated by said crank, a rotary looper-shaft disposed within said inclined work-supporting arm and connected to said vertical shaft, and feeding mechanism disposed within said inclined work-supporting arm and actuated by said looper-shaft.
3. A sewing machine having a frame including a base, a hollow standard rising from said base, a hollow work-supporting arm inclined at an angle to said standard and joining the latter adjacent said base, and feeding mechanism disposed within said work-supporting arm and including a four-motion feed-dog working substantially in a vertical plane transversely of said work-supporting arm.
4. A sewing machine having a frame including a base, a hollow standard rising from said base, a lateral bracket-arm carried by said standard, a hollow work-supporting arm inclined at an angle to said standard and joining the latter adjacent said base, a reciprocating needle carried by said bracket-arm substantially parallel to said standard, means carried by the work-supporting arm for co-operation with said needle in the formation of stitches, and feeding mechanism disposed within said work-supporting arm and including a four motion feed-dog and operative connections arranged to feed the work transversely of the plane of the needle and work-supporting arm.
5. A sewing machine having a frame including a base, a hollow standard rising from said base, a hollow work-supporting arm inclined at an angle to said standard and joining the latter adjacent said base, a substantially horizontal cloth-plate at the free end of said work-supporting arm, and feeding mechanism disposed within said work-supporting arm and including a four-motion feed-dog working substantially vertically in an aperture in said cloth-plate and arranged to feed the work transversely to the plane of said standard and work-supporting arm.
6. A sewing machine having a frame including a base, a hollow standard rising from said base, a hollow work-supporting arm inclined at an angle to said standard and joining the latter adjacent said base and feeding mechanism including a feed-bar having vertical and inclined portions disposed, respectively, in said standard and inclined work-
- supporting arm, and means for actuating said feed-bar.
7. A sewing machine having a frame including a base, a hollow standard rising from said base, a hollow work-supporting arm inclined at an angle to said standard and joining the latter adjacent said base, an inclined looper-shaft disposed within and longitudinally of said work-supporting arm, a feed-bar having a vertical portion disposed within said standard and an inclined portion rigidly connected to said vertical portion and disposed within said work-supporting arm, a feed-dog carried by said feed-bar at the free end of said work-supporting arm, said feed-bar being pivotally hung within said standard at a point substantially level with said feed-dog, means connected to said looper-shaft for imparting rising-and-falling and feed-and-return movements to said feed-bar, and means for guiding said feed-bar.
8. A sewing machine having a frame including a base, a hollow standard rising from said base, a hollow work-supporting arm inclined at an angle to said standard and joining the latter adjacent said base, an inclined looper-shaft disposed within and longitudinally of said work-supporting arm, a feed-bar having a vertical portion disposed within said standard and an inclined portion rigidly connected to said vertical portion and disposed within said work-supporting arm, a feed-dog carried by said feed-bar at the free end of said work-supporting arm, said feed-bar being pivotally hung within said standard at a point substantially level with said feed-dog, means connected to said looper-shaft for imparting rising-and-falling and feed-and-return movements to said feed-bar, and means for guiding said feed-bar.
9. The combination with a sewing machine frame, of a feed-bar having at one end a fixed universal-joint connection with said frame, a feed-dog carried at the other end of said feed-bar, and feed-operating means connected to said feed-bar between said universal-joint and said feed-dog for imparting rising-and-falling and feed-and-return movements to the latter.
10. The combination with a sewing machine frame including a throat-plate, of a feed-bar having at one end a fixed universal-joint connection with said frame disposed substantially at the level of said throat-plate, a feed-dog carried at the other end of said feed-bar and operating through said throat-plate, and feed-operating means connected to said feed-bar between said universal-joint and said feed-dog for imparting rising-and-falling and feed-and-return movements to the latter.

11. The combination with a sewing machine frame of a feed-bar having at one end a fixed universal-joint connection with said frame, a feed-dog carried at the other end of said feed-bar, and feed-operating means connected to said feed-bar between said universal-joint and said feed-dog for imparting rising-and-falling and feed-and-return movements to the latter, said feed-operating means comprising
5 a drive shaft, feed-eccentrics on said shaft, and operative connections between said eccentrics and said feed-bar.

12. A sewing machine having a frame including a base, a standard rising from said base, a work-supporting arm joined to said standard, and feeding mechanism including a feed-bar disposed within and lengthwise of said work-supporting arm, a universal-joint connection between one end of said feed-bar
15 and said frame within said standard, a feed-dog carried by said feed-bar at the free end of said work-supporting arm, means for imparting rising-and-falling movements to said feed-bar, and means for imparting feed-and-
20 return movements to said feed-bar in a direction across the work-supporting arm.
25

In testimony whereof, I have signed my name to this specification.

RUDOLPH BECKER.
